9 Claims. (Cl. 172—240)

Electromagnetic hammers, consisting of solenoids i. e. two or several windings and an iron core or spindle moving to and fro through these solenoids and working upon a cutting chisel, are previously known.

The present invention relates to electromagnetic hammers consisting of one or several electromagnets, i. e. windings on fixed iron cores in which the magnetic lines of force may be concentrated and of an iron spindle moving to and fro. These hammers being supposed to be held by hand during operation are subjected to forcible vibrations, which may cause a derangement of the current interrupter device if mechanically connected to the hammer.

The present invention provides a hammer in which said device is mechanically separated and conveniently disposed remotely from the hammer the latter being connected with the interrupter device exclusively through electrical conductors.

By designing the iron cores of the electromagnets with a circular shape and the armature in the shape of a plate, practically the entire electromagnetic flux is forced to pass through the iron cores and the armature as shown on the drawing. In case alternating current is used the iron cores should be divided into thin sheets. Such a core may be composed of an iron sheet spindle insulated with paper.

Further considerable power losses occur in the hammer as the spindle or that part which transfers the reciprocating motion of the armature to the cutting chisel is passing through the magnetic field. This appears as a restraining effect upon the movement of the spindle and the armature. The same result is obtained also if the cutting chisel itself is extended through the yoke, the spindle then being kept away from the magnetic field. The material in this spindle is thus of vital importance for the functioning of the apparatus and only the very best steel is fit for use owing to the considerable strains occurring in operation. When ordinary steel is used, the above mentioned power losses are unavoidable for which reason the spindle is made of a material that is non-magnetic or nearly non-magnetic at normal temperature and yet of good resistance, for instance austenitic manganese- or nickel-steel.

The invention will now be described in detail with reference to the accompanying drawing showing an embodiment of a hammer-reciprocating motor system.

Fig. 1 is a longitudinal cross-sectional detail of one embodiment of the invention;

Fig. 2 is a transverse cross-sectional view of another embodiment; and

Fig. 3 is a longitudinal sectional detail of this other embodiment.

The hammer shown in Fig. 1 is provided with two electromagnets a_1, a_2 , and two electromagnets b_1, b_2 , of which the two former and the two latter are in combination and are alternately energized and thus attract the armatures c in opposite directions. The electromagnets are preferably of the so-called pot type in which the cylindrical coil is inserted in the space between an outer magnet shell and an inner tubular core coaxial therewith. Through the bore of the inner core the spindle d is passed. The free ends of said shell and said core face the space in which the armature c is movable whereas their opposite ends are magnetically united. The armatures operate the cutting chisel e by means of the common spindle d . The alternating energization of the electromagnets is brought about by the interrupter or switch device, shown below to the left of the hammer.

This switch device consists principally of a two-way switch operated by two electromagnets a and b , between which the armature c may reciprocate. The switch armature is fixed upon the spindle d_1 , on which also an insulated contact e_1 is fixed. When the armature is moving to and fro between the electromagnets, the contact e_1 is moving between the fixed branch contacts f_1 and f_2 , and thus alternately interrupting the current supply from the positive pole through the two electromagnet circuits of the hammer and further through one of the switch electromagnet circuits. It appears from the diagram that this is going on alternately. k_1 and k_2 are two condensers connected between the point g and the both contacts f_1 and f_2 , in order to counteract sparking at the interruptions between f_1 or f_2 respectively and e . The space between f_1 and f_2 may also be filled out with a hard insulating mass as for instance potstone. The ends of the contact e' are to be insulated with a similar mass in order to prevent sparking between the contacts f_1 or f_2 respectively and e' there being no airgap for a possible spark between these contacts.

The system operates as follows: In the position shown in Fig. 1 the contact e_1 receives positive potential and current flows through the stationary contact f_1 , one of the conductors to the hammer, the two hammer coils a_1 and a_2 in parallel, back through a conductor to the switch device, through the switch coil b , and to the nega-

- tive pole. Accordingly, the hammer armature *c* is retracted upwards whereas the switch armature *c*₁ is pulled to the right thereby shifting the contacts. Upon completed shifting the contact 5 *f*₂ will, instead of *f*₁, receive positive potential. The coils *a*₁ and *a*₂ are now deenergized and the mutually parallel-connected hammer-impacting coils *b*₁ and *b*₂ are energized. Further the coil *b* is deenergized and the coil *a* energized. The 10 armature *c* is forced to strike downwards whereas, at the same time, the coil *a* attracts the armature *c*₁ to the left into the position illustrated and the same cycle of operation will be repeated once more and so on.
- 15 In the embodiment shown in Figs. 2 and 3 there are provided two hammer impacting coils *b*₃ and *b*₄ as in the embodiment in Fig. 1 but only one hammer retracting coil *a*₃, it being understood that the impacting impulse should be greater 20 than the retracting impulse.
- The interrupter device may of course be carried out in different ways and is not limited to the embodiment shown in the drawing.
- We claim:
- 25 1. A hammer-reciprocating motor system, comprising a hammer-reciprocating armature, two hammer-electromagnets for the alternate attraction of said hammer armature in opposite directions, two separate electric current paths for the 30 alternate energization of said hammer-electromagnets, a remote two-way switch, a switch reciprocating armature, two switch actuating coils for the alternate attraction of said switch armature in opposite directions, a source of current 35 connected to a common contact of the two-way switch and to common terminals of the switch actuating coils, and two separate series circuits from the other terminals of these coils to the branch contacts of the two-way switch, each circuit 40 permanently including one of the hammer current paths.
2. A hammer-reciprocating motor system, comprising a disc-shaped, hammer-reciprocating armature, two hammer-electromagnets for the alternate attraction of said hammer armature in opposite directions, two separate electric current paths for the alternate energization of said hammer-electromagnets, a remote two-way switch, a switch reciprocating armature, two switch actuating coils for the alternate attraction of said switch armature in opposite directions, a source of current 45 connected to a common contact of the two-way switch and to common terminals of the switch actuating coils, and two separate series circuits from the other terminals of these coils to the branch contacts of the two-way switch, each circuit 50 permanently including one of the hammer current paths.
3. A hammer-reciprocating motor system, comprising a hammer-reciprocating armature comprising a non-magnetic core supporting spaced apart discs of magnetic material, hammer-electromagnets for the attraction of said hammer armature alternately in opposite directions, two 55 mutually insulated electric current paths for the alternate energization of said hammer electromagnets, a remote two-way switch, a switch reciprocating armature, two switch actuating coils for the alternate attraction of said switch armature in opposite directions, a source of current 60 connected to a common contact of the two-way switch and to common terminals of the switch actuating coils, and two separate series circuits from the other terminals of these coils to the branch contacts of the two-way switch, each circuit 65 permanently including one of the hammer current paths.
4. A hammer-reciprocating motor system, comprising a hammer-reciprocating armature comprising a non-magnetic core supporting spaced apart discs of magnetic material, two hammer impacting magnet coils and one hammer retracting magnet coil for the alternate attraction of said hammer armatures in opposite directions, a remote two-way switch, a switch reciprocating armature, two switch actuating magnet coils for the alternate attraction of said switch armature in opposite directions, and a source of current 70 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coil. 80
5. A hammer-reciprocating motor system, comprising a hammer-reciprocating armature comprising a non-magnetic core supporting spaced apart discs of magnetic material, two hammer impacting magnet coils and two hammer retracting magnet coils for the alternate attraction of said hammer armature in opposite directions, a remote two-way switch, a switch reciprocating armature, two switch actuating magnet coils for the alternate attraction of said switch armature in opposite directions, and a source of current 85 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coil. 90
6. A hammer-reciprocating motor system, comprising a hammer reciprocating armature comprising a non-magnetic spindle supporting spaced apart discs of magnetic material, two hammer impacting magnet coils and one hammer retracting magnet coil for the alternate attraction of said hammer armature in opposite directions, a remote two-way switch, a switch reciprocating armature, two switch actuating magnet coils for the alternate attraction of said switch armature in opposite directions and a source of current 95 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coils. 100
7. A hammer-reciprocating motor system, comprising a hammer reciprocating armature comprising a non-magnetic spindle supporting spaced apart discs of magnetic material, two hammer impacting magnet coils and two hammer retracting magnet coils for the alternate attraction of said hammer armature in opposite directions, a remote two-way switch, a switch reciprocating armature, two switch actuating magnet coils for the alternate attraction of said switch armature in opposite directions and a source of current 105 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coils. 110
8. A hammer-reciprocating motor system, comprising a hammer reciprocating armature comprising a non-magnetic spindle supporting spaced apart discs of magnetic material, two hammer impacting magnet coils and two hammer retracting magnet coils for the alternate attraction of said hammer armature in opposite directions, a remote two-way switch, a switch reciprocating armature, two switch actuating magnet coils for the alternate attraction of said switch armature in opposite directions and a source of current 115 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coils. 120
9. A hammer-reciprocating motor system, comprising a hammer reciprocating armature comprising a non-magnetic spindle supporting spaced apart discs of magnetic material, two hammer impacting magnet coils and two hammer retracting magnet coils for the alternate attraction of said hammer armature in opposite directions, a remote two-way switch, a switch reciprocating armature, two switch actuating magnet coils for the alternate attraction of said switch armature in opposite directions and a source of current 125 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coils. 130
10. A hammer-reciprocating motor system, comprising a hammer reciprocating armature comprising a non-magnetic spindle supporting spaced apart discs of magnetic material, two hammer impacting magnet coils and two hammer retracting magnet coils for the alternate attraction of said hammer armature in opposite directions, a remote two-way switch, a switch reciprocating armature, two switch actuating magnet coils for the alternate attraction of said switch armature in opposite directions and a source of current 135 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coils. 140
11. A hammer-reciprocating motor system, comprising a hammer reciprocating armature comprising a non-magnetic spindle supporting spaced apart discs of magnetic material, two hammer impacting magnet coils and two hammer retracting magnet coils for the alternate attraction of said hammer armature in opposite directions, a remote two-way switch, a switch reciprocating armature, two switch actuating magnet coils for the alternate attraction of said switch armature in opposite directions and a source of current 145 connected to a common contact of the two-way switch and to common terminals of the switch actuating coils, and two separate series circuits from the other terminals of these coils to the branch contacts of the two-way switch, one circuit including the two hammer impacting coils, and the other circuit the retracting coils. 150

prising a hammer reciprocating armature comprising a non-magnetic core supporting spaced apart discs of magnetic material, two mutually parallel-connected hammer impacting magnet coils and one hammer retracting magnet coil for the alternate attraction of said hammer armature in opposite directions, a remote two-way switch, a switch reciprocating armature, two switch actuating magnet coils for the alternate attraction 5 of said switch armature in opposite directions, and a source of current connected to a common contact of the two-way switch and to common terminals of the switch actuating coils, and two separate series circuits from the other terminals of these coils to the branch contacts of the two-way switch, one circuit including the two hammer impacting coils, and the other circuit the 10 retracting coil.

9. A hammer-reciprocating motor system, comprising a hammer reciprocating armature comprising a non-magnetic core supporting spaced 15

apart discs of magnetic material, two mutually parallel-connected hammer-impacting magnet coils, and two mutually parallel-connected hammer retracting magnet coils for the alternate attraction of said hammer armature in opposite directions, a remote two-way switch, a switch reciprocating armature, two switch actuating magnet coils for the alternate attraction of said switch armature in opposite directions, and a source of current connected to a common contact of the two-way switch and to common terminals of the switch actuating coils, and two separate series circuits from the other terminals of these coils to the branch contacts of the two-way switch, one circuit including the two hammer impacting coils, and the other circuit the 20 retracting coils.
